UNITED STATES PATENT OFFICE.

JOHN THOMAS PEARMAN, OF LAKE CITY, ARKANSAS.

NUT-LOCK.

SPECIFICATION forming part of Letters Patent No. 723,910, dated March 31, 1903.

Application filed April 26, 1902. Serial No. 104,853. (No model.)

To all whom it may concern:

Be it known that I, JOHN THOMAS PEARMAN, a citizen of the United States, residing at Lake City, in the county of Craighead and 5 State of Arkansas, have invented a new and useful Nut-Lock, of which the following is a specification.

This invention relates to improvements in nut-locks, and has for its object to improve 10 the construction of nut-locks and to provide a simple, effective, and inexpensive device which is adapted for use in connection with any form of nut and in any locality where nuts are employed.

15 The device may be employed in any desired locality, but is more particularly applicable to railway-rail joints, and for the purpose of illustration it is shown in the drawings thus applied.

20 Figure 1 is a side view representing the device applied to a railway-rail joint. Fig. 2 is a transverse section on the line xx of Fig. 1. Fig. 3 is a sectional view on the line yy of Fig. 1.

25 The adjacent sections of the railway-rails are shown at 10 11, the coupling-bars or "fish-plates" at 12 13, respectively, the binding-bolts at 14, and the nuts at 15. The coupling-plates 12 and 13 may be of the ordinary 30 construction or of special construction.

35 Formed in the plate 12 adjacent to the perforation for the bolt is a recess having the side 17^a next the bolt straight and the other side doubly inclined, as at 17^b, or both vertically and transversely, so that the recess is doubly wedge-shaped on one side, the transverse inclination being "undercut." (See Fig. 3.) Within this recess a key-plug 18 is 40 adapted to fit, having one side straight and conforming to and engaging the straight side of the recess and the other side doubly inclined and conforming to and engaging the doubly-inclined side of the recess, as shown. The key-plug extends outward beyond the face 45 of the plate, so that it engages one side of the nut 15, and thus prevents it from turning. By the double inclination of the recess the plug is not only held by a wedge force, but also prevented from moving outward from the face 50 of the plate. This is an important feature of the invention and adds materially to the efficiency of the device, as the key-plug is there-

by rendered self-locking and all danger of displacement obviated. When employed in connection with the coupling-plate of a railway-rail joint, the plate will generally have spaced perforations adapted to embrace all the bolts of the joint and the recesses formed adjacent to the perforations, as indicated. 55

In applying the nut-lock to bolts in use in connection with railway-rail joints the recess for the reception of the wedge may be formed in any stationary object, such as a washer-plate or the adjacent portion of the frame, bed-plate, or other feature of a machine. 60

The key-plug is provided with a hood-like extension 19, projecting laterally and forming a covering to the nut 15 and also affording an additional support to the nut by engaging it on the opposite side by the outer wall of the hood portion, as shown. The hood-like projection thus serves the double purpose of a shield or guard to the nut and also as an additional support thereto. At 75 the upper end the shield portion 19 is formed with a flange or rib 19^a, extending over the upper edge of the plate and affording an additional holding means.

By this simple means a very simple, effective, and inexpensive means for locking a nut in place is produced, which may be readily applied in the various localities where nut-locks are required. 80

The device may be of any size to adapt it to all the various sizes of nuts and bolts. 85

Having thus described my invention, what I claim is—

1. As a new article of manufacture, a nut-lock comprising a hood to receive a nut and provided at one of its lateral edges with a wedge for engaging an undercut recess. 90

2. A nut-lock comprising a washer-plate perforated to receive the bolt, and having an inwardly-tapered recess adjacent to said perforation, the side of said recess next said perforation being straight and the other side inclined longitudinally and transversely, a key-plug having one straight and one inclined side corresponding to and engaging said recess and extending into engagement with the nut, and a shield integral with said key-plug and adapted to inclose the nut, substantially as described. 95 100

3. A nut-lock comprising a washer-plate perforated to receive the bolt, a recess in said washer-plate adjacent to said perforation, a key-plug engaging said recess and extended to engage the nut, and a shield carried by said key-plug and inclosing the nut, substantially as described.

4. A nut-lock comprising a washer-plate perforated to receive the bolt, and having a recess adjacent to said perforation, a key-plug engaging said recess and extended to engage the nut, a shield integral with said key-plug and inclosing the nut, and with a flange extended to engage the washer-plate, substantially as described.

15 5. In a nut-lock, a railway-rail-joint coupling-plate having a washer-plate integral

therewith, said washer-plate having perforations corresponding to the perforations in said coupling-plate, and also having recesses 20 adjacent to said perforations and provided with transversely and longitudinally inclined sides, and key-plugs correspondingly inclined and engaging said recesses, and extended to engage the nuts, substantially as 25 described.

In testimony that I claim the foregoing as my own I have hereto affixed my signature in the presence of two witnesses.

JOHN THOMAS PEARMAN.
